UNITED STATES PATENT OFFICE.

CHARLES G. SHEPARD AND PETER ADAMS, OF BUFFALO, NEW YORK; SAID ADAMS ASSIGNOR TO WALTER J. SHEPARD, OF SAME PLACE.

DESIGN FOR A TEA OR COFFEE POT HANDLE.

SPECIFICATION forming part of Design No. 19,361, dated October 15, 1889.

Application filed July 8, 1889. Serial No. 316,845. Term of patent 7 years.

To all whom it may concern:

Be it known that we, CHARLES G. SHEPARD and PETER ADAMS, citizens of the United States, residing at Buffalo, in the county of Erie and State of New York, have invented and produced a new and original Design for Tea or Coffee Pot Handles, of which the following is a specification, reference being had to the accompanying single figure of the drawing, forming part thereof.

The leading feature of our design consists of raised scalloped surfaces formed on the sides of the handle and each composed of a series of transverse rounded ribs arranged side by side within the inner and outer edges of the handle.

A is the straight and obliquely arranged main portion of the handle. b is the upper arm connected with the upper end of the main portion A by a curved portion c and d, the lower arm forming a continuation of the lower end of the main portion A.

e represents a scalloped or ribbed surface composed of transverse rounded ribs or curved

bands arranged side by side on both lateral faces of the handle and extending from near the lower end of the main portion upwardly over the curved connecting portion c to the upper arm b.

What we claim is—

The design for a pot-handle herein shown and described, the same consisting of an oblique straight main portion, an upper arm connected with said main portion by a curved portion, and a raised scalloped ornament extending continuously over the sides of the handle from near the lower end of the oblique main portion upwardly over the latter and over the round connecting portion and forwardly over the rear portion of the upper arm, as shown.

Witness our hands this 1st day of July, 1889.

CHARLES G. SHEPARD.
PETER ADAMS.
